(57) **CLAIM**

The ornamental design for a body armour plate, as shown and described.

DESCRIPTION

FIG. 1 is a front elevational view of a body armour plate showing my new design.

FIG. 2 is a top edge view thereof; the bottom edge view being a mirror image; and,

FIG. 3 is a side edge view thereof; the opposite side view being a mirror image.

The crosshatching represents shading and forms no part of the overall design.
